DESIGN FOR A BOX OR SIMILAR CONTAINER

Benson Storfer, New York, N. Y.

Application March 26, 1940, Serial No. 91,244

Term of patent 14 years

To all whom it may concern:

Be it known that Benson Storfer, a citizen of the United States and resident of New York, in the county of New York and State of New York, has invented a new, original, and ornamental Design for a Box or Similar Container, of which the following is a specification, reference being had to the accompanying drawing, forming part thereof, in which,

Fig. 1 is an elevational view of a box or similar container embodying my new design;

Fig. 2 is a side view thereof; and

Fig. 3 is a cross-sectional view taken substantially on the line 3—3 of Fig. 1.

I claim:

The ornamental design for a box or similar container, substantially as shown.

BENSON STORFER.
